DESIGN FOR A JEWELRY FINDING FOR PINS OR THE LIKE

Fritz Regelmann, Cranston, R. I., assignor to Carl-Art, Inc., Providence, R. I., a corporation of Rhode Island

Application July 2, 1937, Serial No. 70,238

Term of patent 3½ years

To all whom it may concern:

Be it known that Fritz Regelmann, a citizen of the United States, residing at 111 Duneden Street, Cranston, in the county of Providence and State of Rhode Island, has invented a new, original, and ornamental Design for a Jewelry Finding for Pins or the like, of which the following is a specification, reference being had to the accompanying drawing, forming part thereof,

In the drawing,

Fig. 1 is a plan view of a jewelry finding for pins or the like showing my new design;

Fig. 2 is a side view thereof.

I claim:

The ornamental design for a jewelry finding for pins or the like, as shown.

FRITZ REGELMANN.
